[57] CLAIM

The ornamental design for a splash rail for countertop, as shown.

DESCRIPTION

FIG. 1 is a perspective view of a splash rail for countertop embodying the features of my new design;

FIG. 2 is a plan view thereof, at an enlarged scale;

FIG. 3 is a front elevational view thereof, at an enlarged scale;

FIG. 4 is a bottom view thereof, at an enlarged scale;

FIG. 5 is a rear view thereof, at an enlarged scale;

FIG. 6 is an end elevation view thereof, at an enlarged scale, the end of the design not shown in FIG. 6 is the mirror image thereof; and

FIG. 7 is a cross-sectional view thereof, at an enlarged scale, taken along the line 7—7 of FIG. 1.

FIG. 1

FIG. 2
